UNITED STATES PATENT OFFICE.

WILLIAM I. CLOUS, OF READING, PENNSYLVANIA.

IRONING-BOARD.

SPECIFICATION forming part of Letters Patent No 336,698, dated February 23, 1886.

Application filed July 9, 1885. Serial No. 171,099. (No model.)

To all whom it may concern:

Be it known that I, WILLIAM I. CLOUS, a citizen of the United States, residing at the city of Reading, county of Berks, State of Pennsylvania, have invented a new and useful Improvement in Ironing-Boards and their Fastenings, of which the following is a specification.

This improvement is more particularly related to that class of ironing-boards which, when in use, are attached to or connected with some other article of household use.

The improvement is applicable to all ironing-boards, tables, or other articles which it is desirable to have occasionally or permanently attached to some rigid object, and at the same time, when desired, may be at once disconnected.

The above objects are attained in the use of the improvements shown in the accompanying drawings, like letters of reference indicating like parts.

Figure 1 represents a board perspectively as arranged in front of a window and attached thereto; Fig. 2, a reverse plan of the board, showing my improved locking and releasing device attached thereto; Fig. 3, a side elevation of a board with the improvement attached; Fig. 4, a detail of the locking and releasing device.

A represents an ironing-board; B, a supporting leg; C, the leg-hinge; D, D', and E, a brace-connection between the leg and board; F, a cleat; G, a fixed strap with a shouldered pivot end, G', secured to the cleat F by screws G². A movable strap, H, fulcrumed at H' upon the cleat, is also provided with a shouldered pivot end, H². A cam, I, provided with a thumb-piece pivoted at I', is set with its center of motion at such distance from the strap H that when said cam is curving outwardly, with the tail of the strap H resting against its body, the fixed shouldered pivot G' will interlock with its eye J, and the pivot H² will swing in between clear of the eye J'. The turn of the cam I, pressing on the tail of the strap H and entering the shouldered pivot H² within its eye J', securely locks the board to the eyes, the cam being so arranged relative

to the piece H that when the latter has its 50 pivot engaged with its eye a line drawn through the center of the cam and the center of its pivot will be nearly at right angles with the strap H, thus removing all tendency to automatically release itself.

The straps may be constructed cheaply of malleable iron, the eyes being the ordinary wire screw-eyes regularly sold in the hardware stores.

The boards may be arranged to rest upon 60 the sill of and in front of the window in the room, it being a desirable position for the same, by inserting the eyes in the facing below the sill, as shown, the cleat F being set back from the end of the board to permit the lap 65 upon the sill. The board may, however, be used at any point in the room, as desired, a block, K, being permanently secured at such points, and the eyes J J' being screwed there-in for connection with the board.

If desired, a spring; L, may be secured to the cleat with its free end in contact with the strap H, so that on release of pressure from the cam the resilience of the spring will force the pivot H² out of connection with its eye J', 75 and the board will at once be free. The majority of users will be satisfied to release the board by hand, first reversing the movement of the cam, which leaves the strap H free, then pulling upon the same to withdraw the 80 pivot H² from the eye J.

Having shown my improvement and described its use and advantages, I desire to claim as follows:

As an improved fastener for ironing-boards and analogous articles, a fulcrumed piece, H, provided with a shouldered pivotal end, H², fulcrumed at H' upon the cleat, and releasably locked by contact with the cam I, provided with a thumb-piece, in combination 85 with the spring L, the fixed piece G, its pivotal end G', and the screw-eyes J J', substantially as and for the purpose set forth.

WILLIAM I. CLOUS.
